SHOE SEWING MACHINE

Karl Engel, Swampscott, Mass., assignor to United
Shoe Machinery Corporation, Borough of Flem-
ington, N. J., a corporation of New Jersey

Application June 4, 1937, Serial No. 146,389

18 Claims. (Cl. 112—47)

The present invention relates to shoe sewing machines, and more particularly to a machine for use in the manufacture of pre-welt shoes.

In the pre-welt type of shoe, the welt is sewed directly to the margin of the upper before the upper is lasted. The operation of lasting the welted upper has heretofore involved certain difficulties in obtaining the proper inturn of the upper adjacent the welt, particularly around the toe portion of the shoe. The difficulty has arisen because of the relative stiffness which the attached welt imparts to the margin of the upper, such stiffness preventing the proper contraction or gathering of the upper along the edge of the toe portion in the lasting operation, and consequently requiring increased stretching of the central portion of the upper to produce a correctly shaped shoe.

The object of the present invention is to provide a shoe sewing machine arranged to attach a welt to an unlasted upper in a novel and improved manner whereby the shaping of the welted upper, and particularly the toe portion thereof, over the last may be carried out with less difficulty, and with more satisfactory results than heretofore.

With this object in view, a feature of the invention comprises the provision in a machine for sewing a welt to an unlasted upper of means for feeding the upper with relation to the welt during the sewing operation to cause the upper to be secured to the welt with the margin of the upper in gathered or puckered condition. By this puckering, the welted upper is given a natural tendency to turn inwardly along the puckered portion of the margin, and caused to assume to a certain extent its lasted shape. As a result, the time and effort required in lasting the shoe are substantially reduced, since less working and stretching of the upper are necessary to secure a satisfactory shape of toe.

The invention is shown and described as embodied, for purposes of illustration only, in a shoe sewing machine having a presser foot which is actuated to clamp and unclamp the work during each stitch forming cycle, the work clamping movement of the presser-foot being utilized through means hereinafter described to feed the upper with relation to the welt during the sewing operation to pucker the upper and cause it to be secured to the welt while in such puckered condition.

It is desirable that a substantial amount of puckering be imparted to the margin of the upper, consistent with a smooth and unwrinkled

appearance of the completed shoe. To achieve this result with various shapes and sizes of uppers, and with leather of different characteristics, another feature of the invention comprises means for adjusting the amount of feeding movement 5 imparted to the upper with relation to the welt whereby the amount of puckering appropriate to the work being sewn may be obtained.

While it has been found advantageous to pucker the margin of the upper around the toe portion during the operation of sewing the welt thereto, it is generally neither necessary nor desirable to pucker other portions of the upper. In order that the puckering may be imparted only to the desired portions of the upper, a further feature of the invention comprises means under the control of the operator for rendering the upper puckering mechanism operative and inoperative without stopping the machine or otherwise interrupting the sewing operation. 20

Other features of the present invention consist of certain constructions, combinations, and arrangements of parts, the advantages of which will be apparent to those skilled in the art from the following description taken in conjunction 25 with the accompanying drawings, in which Fig. 1 is a view in left side elevation of a shoe sewing machine embodying the preferred form of the invention, certain of the actuating mechanisms for the stitch forming and work feeding devices being indicated in dotted line; Fig. 2 is a view in front elevation, on a somewhat larger scale, of the head and base portions of the machine illustrated in Fig. 1; Fig. 3 is a detail perspective view of the portion of the machine adjacent the sewing point, illustrating the stitch forming and work feeding devices, and showing the presser foot and puckering point in raised position; Figs. 4 to 7 are a series of views in front elevation of the portion of the machine 30 shown in Fig. 3, taken at different times in the stitch forming cycle of operations, the work being shown partly in section; Fig. 8 is a view similar to Fig. 3, but with the puckering lever locked in inoperative position, and with the work 35 indicated in outline; Fig. 9 is a view similar to Fig. 3, but illustrating a modified form of puckering device mounted on the presser foot of the machine; Fig. 10 is an enlarged detail view in front elevation of the portion of the machine 40 illustrated in Fig. 9, with the work in sewing position; Fig. 11 is a detail plan view, partly in section, of the presser foot and puckering lever, taken along the line 11—11 of Fig. 10; and Fig. 12 is a perspective view of the toe portion of an 45

unlasted upper and attached welt as sewn by the machine embodying the preferred form of the invention.

The shoe sewing machine illustrated in Figs. 1 and 2 is generally known as the "Puritan" machine, and is well adapted for sewing a welt to an unlasted upper by reason of its high sewing speed. The stitch forming and work feeding devices of the machine comprise a straight hook 10 needle 2, an awl 4, a needle threading looper 6, and a needle cast-off 8, these members being actuated in proper timed relation by connections from a cam shaft 10 to sew a chain stitch seam in the work.

15 The cam shaft 10 is located in the head portion 12 of the machine frame, and is provided with clutch mechanism for starting and stopping the machine comprising a driven member 14 secured to the shaft and a driving member 16 rotatable thereon. The driving member is rotated continuously by means of belt 18 from a motor, not shown, in the base of the bench or pedestal 20 upon which the machine is mounted. By means of the usual treadle, not shown, acting 25 through rod 22 and lever 24, the driving member 16 is moved axially to bring the cone clutch surfaces, indicated at 26 and 28, into engagement to start the machine. The machine is stopped by releasing the treadle, permitting spring 30 to 30 rock lever 26 to disengage the clutch and also to apply a friction brake 32 to reduce the time required to bring the cam shaft to rest.

The needle 2 is clamped in the end of a needle bar 34, while the cast-off 8 is secured in a fitting 35 36 clamped to the end of the cast-off bar 38. The needle bar 34 and the cast-off bar 38 are mounted to permit vertical sliding movement in an arm 40 secured to a rock shaft 42 pivotally mounted in the base of the machine on screw points 44. 40 The needle is vertically reciprocated in the arm 40 by means of an eccentric 45 on the cam shaft 10 by connections comprising an eccentric strap 46 connected by rod 48 to an arm on rock shaft 50 in the base of the machine, the other end of 45 the rock shaft having an arm 52 connected to the needle bar 34 by link 54. The cast-off bar 38 is similarly actuated from eccentric 56 by connections comprising eccentric strap 58, rod 60, rock shaft 62, arm 64 and link 66.

50 The work is fed intermittently past the sewing point by movement of the needle 2 in a horizontal direction, the arm 40 being rocked in work-advancing direction while the needle is in the work by connections between the cam shaft 10 and the 55 rock shaft 42 on which arm 40 is mounted, the retracting stroke of the arm 40 being made while the needle is withdrawn from the work. The rock shaft actuating mechanism comprises an eccentric 68 on the cam shaft 10, a yoke 70 embracing the eccentric, and a feed lever 72 secured at one end to the yoke 70 and pivotally attached at the other end to an arm 74 secured to the rock shaft 42. By mechanism indicated generally at 60 78, and fully illustrated and described in U. S. Patent No. 490,854, issued January 31, 1893, to Frank W. Merrick, the effective center about which the lever 72 is rocked by eccentric 68 may be raised or lowered by handle 78 to change the relative lengths of the arms of the feed lever 72 65 above and below such center, thereby varying the arc of rock of the needle supporting arm 40 and consequently the rate of feed imparted to the work.

The awl 4 is clamped in the lower end of an awl bar 80 mounted to permit vertical sliding move-

ment in the head portion of the machine. The awl bar is reciprocated to cause the awl to pierce the work by means of crank disc 82 on the cam shaft 10 and pitman 84.

The looper 6 for placing the thread in the hook of the needle is actuated to travel in a circular or elliptical path around the needle by mechanism similar to that illustrated and described in U. S. Patent No. 490,856, issued January 31, 1893, to Frank W. Merrick to which reference should be made for a complete description. Briefly, the mechanism comprises a sleeve 86 provided with a depending arm 88 in which the looper 6 is mounted, a convex-surface eccentric 90 on the cam shaft of the machine, an eccentric 1 strap 92 surrounding the eccentric and pivotally secured at its lower end to the sleeve 86, and a rod 94 extending within the sleeve and pivotally mounted at its other end on center screws 96 in the head of the machine.

The needle thread on its way to the looper 6 is drawn through a wax pot 98 of conventional construction and arrangement, mounted on the head portion of the machine frame.

The work is clamped against the work support 100 during a portion of each stitch forming cycle by means of a presser foot 102 mounted on a presser foot bar 104 arranged to slide vertically in the front portion of the head of the machine. A flat spring 106 adjustably secured at one end 30 to the frame of the machine and bearing at the other end against the upper end of the presser foot bar holds the presser foot normally pressed upon the upper surface of the work. The presser foot is raised to permit the work to be fed by 35 the needle by mechanism actuated from the cam shaft 10, and more fully illustrated and described in U. S. Patent No. 629,108, issued July 18, 1899, to Frank W. Merrick. An eccentric 108 on the cam shaft 10 is surrounded by an 40 eccentric strap 110 pivotally attached to an arm 112 of rock shaft 114 mounted on screw points 116 in lugs projecting from the head of the machine. An arm 118 on the front end of the rock shaft 114 is adapted, when rocked in an upward 45 direction, to engage lug 120, causing clutching mechanism indicated at 122 to grip and lift the presser foot bar 104.

The clutching mechanism 122 comprises a cylindrical nut 124 threaded to engage a rapid-pitch screw thread formed in the upper portion 50 of the presser foot bar 104. The nut fits loosely inside a cylindrical bore in the block 126, of which the lug 120 is a part. The nut 124 is free to rotate within the block and the presser foot 55 bar is therefore movable vertically relative to the same except when the arm 118 is rocked to engage the lug 120 and tilt block 126, locking the nut against rotation in the bore and, therefore, against movement relative to the presser foot bar.

The amount of rise of the presser foot may be 60 adjusted by means of a sleeve 128 which surrounds the threaded portion of the presser foot bar and is provided with an offset portion within which the block 126 is positioned. The sleeve is urged downwardly in the head of the machine by a flat spring 130 mounted below the presser foot spring 106, the descent of the sleeve during the clamping movement of the presser foot being limited by nuts 132 threaded to the upper portion 70 of the sleeve. With the nuts 132 at the top of the sleeve, maximum rise of the presser foot is obtained due to the fact that arm 118 engages lug 120 and commences to lift the presser foot early in the upward rocking movement of said 75

5 arm, while with the nuts screwed down onto the sleeve, the presser foot lifts but slightly, since the arm 118 does not come into contact with lug 120 until the arm has substantially completed its upward movement. It is evident that with the mechanism described, for any given setting of the nuts 132 on sleeve 128 the presser foot is always raised the same distance above the work regardless of the thickness of such work, a desirable feature in connection with the upper puckering mechanism hereinafter described.

10 The presser foot is prevented from coming into contact with the work support when there is no work in the machine by means of a block 134 15 clamped to the presser foot bar 104 and provided with a pin 136 projecting through a slot 138 in the frame of the machine. The block is so positioned on the presser foot bar that pin 136 bottoms in the slot when the presser foot just clears 20 the work support.

To permit the work to be placed in and withdrawn from operative position in the machine, means are provided for lifting the presser foot comprising a treadle, not shown, which is connected by rod 140 to one end of a lever 142 pivotally mounted on the frame of the machine, the other end of the lever being adapted to engage the underside of the pin 136.

25 The presser foot 102, best shown in the detail views, comprises a work pressing portion or platen 144 adapted to engage the outside of the shoe upper 146, and a welt guiding portion comprising a lip 148 through which the welt 150 is drawn and by which the welt is supported adjacent the 30 sewing point during the sewing operation.

35 The work support 100 is provided with a portion 152 having a curved surface, upon which the inside of the upper rests, such curvature preventing distortion of the upper during the sewing operation, particularly when working around the toe and heel portions of the shoe, as illustrated in Figs. 5 to 7. An edge gage 154 secured to the flat portion of the work support by screws 156 is provided for guiding the upper.

40 The mechanism for puckering the upper comprises a lever 158 pivotally mounted in an extension of the needle slot 160 on screw 162. The lever is provided at one end with a feed point 164 which is pressed upwardly against the inside of 45 the upper 146 by means of spring 166 stretched between the other arm of the lever and a hook 168 on the work support arm.

50 When the presser foot is in work clamping position, the feed point is substantially flush with the surface of the work support, as indicated in 55 Figs. 5 to 7. As the presser foot is raised, spring 166 rocks the puckering lever to cause the feed point 164 to lift the upper from the work support, forming a broad elevation or fold 169, as illustrated in Fig. 4. Upon downward movement of the presser foot, the feed point is forced downwardly, rocking the puckering lever about its pivot and imparting to the upper a forward feeding movement, the upper sliding along the presser 60 foot platen 144. Since the downward movement of the presser foot is timed to take place while the needle is through the work, the result of feeding the upper by the above mechanism is to gather or pucker that side or portion of the broad 65 fold 169 of the upper lying between the feed point 164 and the needle 2 (see Fig. 4).

70 The upper is secured to the welt while in puckered condition by actuation of the sewing instrumentalities to sew a chain stitch seam in the 75 work, as illustrated in Figs. 5 to 7. In Fig. 5, the

presser foot has clamped the work while the needle is drawing the loop of thread into the work. Fig. 6 shows the needle at the bottom of its stroke and still in its forward position, with the awl 4 descending to pierce the welt and puckered upper. In Fig. 7, the needle supporting arm 40 has been rocked to retracted position to permit the needle to pass up through the hole made by the awl, and the looper is about to lay the thread in the hook of the needle, following which the pressure foot is raised and the puckering lever is actuated to form a fold or pucker in the upper, as shown in Fig. 4. The work is then fed and the presser-foot lowered, bringing the parts back to the position shown in Fig. 5.

15 The amount of puckering imparted to the upper may be controlled by the operator through adjustment of a stop screw 170 by which the arc of rock of the puckering lever may be limited. The stop screw is threaded in an arm 172 mounted on 20 the work support 100, and is provided with a check nut 174. In addition, adjustment of the rise of the presser foot by means of nuts 132 serves to change the rate of puckering, since the stroke of the puckering lever, except as limited by stop 25 screw 170, depends on the rise of the presser foot. As has already been pointed out, the presser foot, for any given setting of nuts 132, lifts a uniform distance above the work, regardless of variations in thickness of the same, and hence the upper is 30 gathered the same amount at each stroke of the presser foot.

35 It is generally desirable that the upper be puckered around the toe portion only of the shoe, and therefore means are provided for locking the 40 puckering lever in inoperative position, these means comprising a lever 176 pivotally mounted on the work support 100 and adapted to be swung under the puckering lever to maintain the latter with the feed point 164 substantially flush with the surface of the work support, (see Fig. 8). The lever 176 may be readily actuated by the operator of the machine so that the puckering lever may be rendered operative and inoperative without stopping the machine or otherwise interrupting the sewing operation.

45 The toe portion of an upper and welt sewn by the machine above described is illustrated in Fig. 12. The puckering of the upper 146 is observable around the toe, and likewise the inturn of the 50 upper adjacent the welt 150, which results in the upper assuming its lasted shape. Since the parts illustrated were sewn with the upper on the same side as the needle, the chain portion of the seam is on the inside of the upper, while the line of 55 single thread loops lies in the welt channel.

55 A modification of the invention is illustrated in Figs. 9 to 11, and is adapted to pucker the upper while sewing the parts with the welt beneath the upper and on the same side as the needle, so that 60 the chain portion of the seam is laid in the welt channel. In this form of the invention the puckering lever is mounted on the presser foot, while the welt guide comprises a portion of the work support.

65 The presser foot is provided with a work engaging platen 180 having an elongated aperture through which the needle passes, the platen along one side of the needle slot being provided with an integrally formed reinforcing rib 182 which 70 extends beyond the platen to form a lug 184 bearing a screw 186 upon which is pivotally mounted the puckering lever 188.

75 The long arm of the puckering lever is formed at its outer end to provide a seat for spring 190.

a guide pin 192 serving to maintain the spring in place. The other end of the spring is seated on one of the lugs 194 by which the presser foot is clamped to the presser foot bar 104.

5 The puckering lever is formed with a curved shoulder or boss 196 adapted to bear against the inside of the upper, as illustrated in Fig. 10, under the action of the spring 190. The downward movement of the lever is limited by a lip 198 formed in the lever and adapted to engage the reenforcing rib 182 when the lever has reached a substantially horizontal position.

10 The short arm of the puckering lever 188 is provided with a portion 200 which is at an angle 15 to the long arm of the lever and serves as a pivot block upon which the feed point 202 is mounted by means of screw 204.

15 The feed point 202 comprises a work-engaging portion 206 having sharpened prongs to insure 20 that the upper will be positively fed during the puckering stroke, particularly when sewing an upper which has been lined. The feed point also includes an arm 208 by which the operator may readily swing the feed point about its pivot to 25 move the work-engaging portion 206 to one side and out of operative contact with the upper, when portions of the upper are to be sewn to the welt where puckering is not required. A lip 210 serves 30 as a stop to permit the feed point to be returned quickly to operative position without stopping the machine, when the puckering operation is to be resumed.

35 The work support 212 is provided with a channel 214 through which the welt passes on its way to the sewing point. A strip 216 of thin resilient material such as spring steel covers a portion of the channel and serves as a support for the upper opposite the prongs 206 of the feed point 202, so that the upper may be fed toward the 40 sewing point independently of and without friction with the welt. The upper is guided to cause the line of stitches to be the proper distance from the edge by means of the usual edge gage 218 adjustably secured to the work support 212 by 45 screws 220.

50 The operation of the above described modification is substantially similar to that of the preferred embodiment of the invention, the descending movement of the presser foot causing the puckering lever 188 to rock in a clockwise direction due to the fact that the boss 196 is maintained in the same horizontal plane by engagement with the inside of the upper. This clockwise rotation causes the prongs of the feed point, 55 which are firmly engaging the upper, to rock from right to left, advancing the upper only toward the needle, which is through the work at this stage in the operation, thereby gathering or puckering the upper between the feed point and the needle. The presser foot, upon completing 60 its downward movement, clamps the work with the upper in puckered condition while the awl pierces the work and the stitch is formed.

65 While the invention has been illustrated and described as embodied in a preferred form and in a modification thereof, and for use on a particular type of shoe sewing machine, it is to be understood that the invention is not limited to such embodiments, or to use on such machines only, but covers all forms and arrangements for puckering an upper during the attachment of a welt to an unlasted upper, except as limited by the appended claims.

70 Where, in the claims, reference is made to 5 "means for guiding a welt and an unlasted upper

to the sewing point with their edges in substantial alignment" this is not to be considered as limiting the invention to a construction in which the upper and welt are guided with their edges exactly coinciding or flush, but also includes a 5 construction in which the upper and welt are presented to the sewing point with their edges more or less offset, that is, with their edges in substantially parallel alignment but not in registration. 10

The nature and scope of the invention having thus been described, what is claimed is:

1. A machine for use in the manufacture of pre-welt shoes having, in combination, means for guiding a welt and an unlasted upper to the 15 sewing point with their edges substantially in alignment, and stitch forming and work feeding devices including a presser foot, a hook needle, an awl, means for moving one of the latter two elements with the work in the line of feed, and 20 means for feeding the upper with relation to the welt during the sewing operation to cause the upper to be sewed to the welt in puckered condition.

2. A machine for use in the manufacture of 25 pre-welt shoes having, in combination, means for guiding a welt and an unlasted upper to the sewing point with their edges substantially in alignment, and stitch forming and work feeding devices including a needle, a presser foot, a work 30 support, and means for feeding the upper with relation to the welt while the needle is through the work to pucker the upper, and for holding the pucker in the upper until the needle again enters the work, to cause the upper to be sewed 35 to the welt in puckered condition.

3. A machine for use in the manufacture of 40 pre-welt shoes having, in combination, means for guiding a welt and an unlasted upper to the sewing point with their edges substantially in alignment, and stitch forming and work feeding devices including a hook needle, a work support, 45 a presser foot and means for actuating the presser foot to clamp and unclamp the work during each sewing cycle, and means for feeding the upper 50 with relation to the welt to pucker the upper between successive penetrations of the work by the needle and holding the pucker until the needle again penetrates the work.

4. A machine for use in the manufacture of 55 pre-welt shoes having, in combination, means for guiding a welt and an unlasted upper to the sewing point with their edges in substantial alignment, and stitch forming and work feeding devices including a hook needle, a presser foot, a 60 work support, and means for feeding the upper with relation to the welt during the sewing operation to pucker the upper, said means including a feed point for engaging the upper and imparting 65 feeding movement thereto.

5. A machine for use in the manufacture of 70 pre-welt shoes having, in combination, means for guiding a welt and an unlasted upper to the sewing point with their edges in substantial alignment, and stitch forming and work feeding devices including a presser foot, a hook needle, 75 means for moving the needle with the work in the line of feed, and means for imparting a supplemental feed to the upper only during the sewing operation to cause the upper to be secured to the welt in puckered condition.

6. A machine for use in the manufacture of 75 pre-welt shoes having, in combination, means for guiding a welt and an unlasted upper to the sewing point with their edges in substantial align- 75

ment, stitch forming and work feeding devices including means for imparting a supplemental feed to the upper only during the sewing operation to cause the upper to be secured to the welt in puckered condition, and means under the control of the operator for rendering inoperative the means for imparting the supplemental feed.

7. A machine for use in the manufacture of pre-welt shoes having, in combination, means for guiding a welt and an unlasted upper to the sewing point with their edges in substantial alignment, stitch forming and work feeding devices including a presser foot, a hook needle, an awl, means for moving one of the latter two elements with the work in the line of feed, and means for feeding the upper with relation to the welt during the sewing operation to pucker the upper, said means having provision for adjustment to vary the relative feeding movement of the upper.

8. A machine for use in the manufacture of pre-welt shoes having, in combination, means for guiding a welt and an unlasted upper to the sewing point with their edges in substantial alignment, stitch forming and work feeding devices including means for feeding the upper with relation to the welt during the sewing operation to pucker the upper, and means controllable by the operator during the operation of the machine to render operative and inoperative the means for imparting said relative feeding movement to the upper.

9. A machine for use in the manufacture of pre-welt shoes having, in combination, means for guiding a welt and an unlasted upper to the sewing point with their edges in substantial alignment, stitch forming and work feeding devices, a presser foot, presser foot actuating mechanism, and means actuated by the presser foot for feeding the upper with relation to the welt to cause the upper to be sewed to the welt in puckered condition.

10. A machine for use in the manufacture of pre-welt shoes having, in combination, means for guiding a welt and an unlasted upper to the sewing point with their edges in substantial alignment, stitch forming and work feeding devices including a needle, a presser foot, devices for actuating the presser foot to cause it to clamp and to release the work, and means including a lever provided with a feed point for engaging the upper and adapted to be rocked by the clamping movement of the presser foot and while the needle is through the work to feed the upper with relation to the welt and to cause the upper to be sewed to the welt in puckered condition.

11. A machine for use in the manufacture of pre-welt shoes having means for guiding a welt and an unlasted upper to the sewing point with their edges in substantial alignment, stitch forming and work feeding devices including a needle, a presser foot, a work support, means provided with a feed point for engaging the upper, and mechanism for actuating said means to cause the feed point to raise the upper from the work support to provide surplus upper between the feed point and the needle and to feed such surplus upper with respect to the welt toward the needle while the latter is in the work to cause the upper to be sewed to the welt in puckered condition.

12. A machine for use in the manufacture of pre-welt shoes having, in combination, means for guiding a welt and an unlasted upper to the sewing point with the welt beneath the upper and with their edges in substantial alignment, stitch

forming and work feeding devices including a needle, a presser foot, movable into and out of clamping relation to the work, and means comprising a lever pivotally mounted on the presser foot and provided with a feed point for engaging the inside of the upper, said lever being rocked by the clamping movement of the presser foot to advance the upper with relation to the welt to cause the upper to be secured to the welt in puckered condition.

13. A machine for use in the manufacture of pre-welt shoes having, in combination, means for guiding a welt and an unlasted upper to the sewing point with the welt beneath the upper and with their edges in substantial alignment, stitch forming and work feeding devices, a presser foot, and means comprising a lever pivotally mounted intermediate its ends on the presser foot and provided with a feed point on one arm thereof for engaging the inside of the upper, a fixed abutment for the other arm of the lever, means for maintaining the second arm in engagement with the abutment whereby downward movement of the presser foot rocks the lever to feed the upper with relation to the welt to cause the upper to be sewed to the welt in puckered condition.

14. A machine for use in the manufacture of pre-welt shoes having means for guiding a welt and an unlasted upper to the sewing point with their edges in substantial alignment, stitch forming and work feeding devices including a needle, a presser foot, a work support, means provided with a feed point for engaging the upper on the opposite side of the upper from the work support, and mechanism for actuating the feed point to cause the point to engage the upper and feed it with relation to the welt toward the needle while the latter is in the work to cause the upper to be sewed to the welt in puckered condition.

15. A machine for use in the manufacture of pre-welt shoes having, in combination, means for guiding a welt and an unlasted upper to the sewing point with the welt above the upper and with their edges in substantial alignment, stitch forming and work feeding devices, a work support, a presser foot movable into and out of clamping position, and means comprising a lever pivotally mounted on the work support and provided with a feed point for engaging the inside of the upper, said lever being rocked by clamping movement of the presser foot to advance the upper with relation to the welt to cause the upper to be secured to the welt in puckered condition.

16. A machine for use in the manufacture of pre-welt shoes having, in combination, stitch forming and work feeding devices, a work support having an aperture therethrough, a presser foot, means on the presser foot and on the work support for guiding a welt and upper respectively to the sewing point with the presser foot between the parts of the work and with their edges in substantial alignment, and supplementary upper feeding means comprising a lever pivotally mounted on the work support and provided with a feed point positioned directly beneath the presser foot and adapted to operate through the aperture in the work support, and means tending to rock the lever in the direction to force the feed point upwardly against the inside of the upper and to lift the same when the presser foot is raised, whereby downward movement of the presser foot rocks the lever in the reverse direction to feed the upper with relation to the

welt to cause the upper to be secured to the welt in puckered condition.

17. A machine for use in the manufacture of pre-welt shoes having, in combination, means for guiding a welt and an unlasted upper to the sewing point with the upper above the welt and with their edges in substantial alignment, stitch forming and work feeding devices, a work support, a presser foot, means comprising a lever pivotedly mounted on the presser foot, an arm pivoted on the lever and provided with a feed point for engaging the inside of the upper, said lever being rocked by clamping movement of the presser foot to advance the upper with relation to the welt to cause the upper to be secured to the welt in puckered condition, and means under the control of the operator for swinging the arm on

the lever to move the feed point out of operative position to permit the sewing operation to be carried out without puckering the upper.

18. A machine for use in the manufacture of pre-welt shoes having means for guiding a welt and an unlasted upper to the sewing point with their edges in substantial alignment, stitch forming and work feeding devices including a needle, a presser foot, a work support, means provided with a feed point for engaging the upper on the same side of the upper as the work support, and mechanism for actuating the feed point to cause the point to engage the upper and feed it with relation to the welt toward the needle while the latter is in the work to cause the upper to be sewed to the welt in puckered condition.

KARL ENGEL.
